United States Patent Office.

GOLDSBURY H. POND, OF RUTLAND, VERMONT.

Design No. 3,961, dated April 5, 1870.

DESIGN FOR A TOBACCO-PIPE.

The Schedule referred to in these Letters Patent and making part of the same.

To all whom it may concern:

Be it known that I, GOLDSBURY H. POND, of Rutland, Rutland county, in the State of Vermont, have invented and produced a new and original Design for a Tobacco-Pipe; and I hereby declare the following to be a full and exact description thereof, reference being had to the accompanying photographs forming part of this specification.

The nature or essence of my invention consists in a design for a tobacco-pipe, in which the exterior is formed in imitation of the surface of a corn-cob, or

the cob of Indian corn or maize, as represented in the accompanying photographic illustration, to which reference is made.

I claim as my invention—

The design for a tobacco-pipe, as described and shown.

GOLDSBURY H. POND.
